His Attorney.

Patented July 13, 1926.

UNITED STATES PATENT OFFICE.

GEORGE W. BOWER, OF SCHENECTADY, NEW YORK, ASSIGNOR TO GENERAL ELECTRIC COMPANY, A CORPORATION OF NEW YORK.

ELECTRIC-CURRENT COLLECTOR.

Application filed December 1, 1925. Serial No. 72,548.

The present invention relates to electric current collectors whereby electric power is communicated from a stationary overhead conductor to a power driven device movable 5 with relation to the stationary conductor and generally known as trolleys.

Overhead trolleys, as heretofore made, are not well adapted for use on traveling cranes, electric mules, etc., where the head room is 10 limited and the amount of power used comparatively light.

The object of my invention is the provision of a hardy and efficient electric current collector which shall occupy very little 15 space and which may be manufactured at low cost.

One embodiment of the invention is shown in the accompanying drawing in which Fig. 1 is a side elevation of the collector in its 20 fully elevated position; Fig. 2 is an end elevation thereof; Fig. 3 is a plan view of the spring-actuating mechanism with the lower pantograph arms shown in section, and Fig. 4 is a part side elevation and part 25 vertical section of the spring actuator.

The frame of the collector is of the diamond or pantographic type and consists of a baseboard 1 with two lower arms 2 of the 30 pantograph pivoted thereto at suitably spaced points by hinges 3, two upper arms 4 of the pantograph pivoted to the upper ends of the lower arms 2 by hinges 5 and a collector shoe support 6 pivoted to the tops of the upper arms 4 by hinges 7 and supported thereby substantially parallel to the base 1. The base 1, arms 2 and 4 and the shoe support 6 are for the sake of lightness 35 made of wooden slabs and the ends of the arms 2 and 4 are cut angularly so that they abut at an angle and in the manner of rule joints to thereby limit the upward movement 40 of the frame as indicated in Fig. 1 with its several arms positioned similar to the sides of a diamond figure.

45 The actuating-spring mechanism consists of a cast iron pedestal 8 bolted to the baseboard 1 between the lower arms 2, a two-armed yoke 9 pivoted on a stub shaft 10 at the top of the pedestal and held thereon 50 by a bolt 11 and a helical torsion spring 12 surrounding cylindrical portions of the pedestal and yoke with its upper end 13 bent over an arm of the yoke 9, while its lower end 14 is held adjustably between spaced

55 lugs 15 at the lower periphery of the pedestal. The free ends of the arms of the yoke 9 are connected by links 16 to the lower frame arms 2 by means of bolts 17 so that, as indicated in Fig. 3, the recoil of the torsion spring tends to move the arms toward the 60 vertical position and yieldingly to maintain the shoe support 6 elevated.

A metallic collector shoe or plate 18 having side ribs 19 and deflected tips 20 is mounted on top the support 6 and secured 65 by bolts 21 which engage at their lower ends with a terminal 22 of the flexible cable 23 extending to the base 1 where it is connected to a stationary terminal 24 held by a binding post 25 to the base and from which the 70 current is led, in the well known manner, to the motor or other translating device.

When in use the collector shoe 18 travels along the underside of the suspended trolley or supply wire (not shown), and by reason 75 of the yielding spring connection it moves up and down according to the variations in elevation of the trolley wire. The limits of such up and down movements of the collector shoe are indicated respectively in the 80 full line and the dotted line positions shown in Fig. 1.

While I have shown and described the best embodiment of the invention known to me, I do not desire to be restricted thereto. 85

What I claim as new and desire to secure by Letters Patent of the United States, is:—

1. An electric current collector comprising a base, pantographic arms pivotally mounted on said base, a pedestal vertically 90 mounted on said base between said pantographic arms, a yoke pivoted on said pedestal, a torsion spring surrounding said pedestal and exerting torque upon said yoke, and links connecting said yoke with said pantographic arms. 95

2. An electric current collector comprising a base, pantographic arms pivotally mounted thereon, a pedestal vertically mounted on said base between said pantographic arms, a horizontally movable yoke pivoted on said pedestal, a torsion spring adjustably connected to said pedestal and exerting torque upon said yoke, and links connecting said yoke to said pantographic arms. 100

105 In witness whereof, I have hereunto set my hand this 30th day of November, 1925.

GEORGE W. BOWER.
